Des. 185,256
Patented May 26, 1959

185,256

ELECTRICAL SWITCH ENCLOSURE

Don J. Arneberg, Milwaukee, Wis., and Richard W. Figgins, Birmingham, Mich., assignors to Square D Company, Detroit, Mich., a corporation of Michigan

Application April 11, 1958, Serial No. 50,445

Term of patent 14 years

(Cl. D26—13)

FIG. 1

FIG. 2

FIG. 3

FIG. 4

FIG. 5

Fig. 1 is a front elevational view of an electrical switch enclosure showing our new design.

Fig. 2 is a side elevational view.

Fig. 3 is a top plan view thereof.

Fig. 4 is a bottom plan view thereof.

Fig. 5 is a rear elevational view thereof.

We claim:

The ornamental design for an electrical switch enclosure, substantially as shown.
